UNITED STATES PATENT OFFICE.

FRANK SWEET, OF COLUMBUS, OHIO.

MECHANICAL COUNTER.

SPECIFICATION forming part of Letters Patent No. 430,708, dated June 24, 1890.

Application filed January 31, 1890. Serial No. 339,112. (No model.)

To all whom it may concern:

Be it known that I, FRANK SWEET, a citizen of the United States, residing at Columbus, in the county of Franklin and State of Ohio, 5 have invented a new and useful Counter, of which the following is a description of its construction and operation.

My invention consists, essentially, of a series of two or three wheels or disks, numbered 10 to 100, made to revolve on a common central pivot by a ratchet-lever for the purpose of counting when applied to any suitable machinery.

The following drawings illustrate my invention:

Figure 1 is a plan view of the complete counter. Fig. 2 is a side elevation of the same. Fig. 3 is an end elevation. Fig. 4 is a rear view of the counter. Fig. 5 is a sectional view through *u u*, Fig. 1.

Similar letters refer to similar parts.

Each disk is numbered, as shown on the plan view, with figures 1 to 100, arranged at regular distances round the entire disk. The lever *b* may be operated at either end by a wedge-shaped piece of metal, or its equivalent, or by a cord, wire, or chain, whichever may be preferable, according to the construction or use of the machine to which the counter 30 is applied.

The counter is set for operation by moving the large disk *f* round on the central pivot *s* till the two ciphers on the disk *f* are opposite the latch *r*, that holds the hammer *l* away 35 from the bell *k*, and the small disk *g* moved round till the cipher thereon is in line with the two ciphers of the large disk *f*, in the position shown on Fig. 1. When the disks are thus arranged, the counter may be set to count 40 any desired number by moving the adjusting-arm *j* round and placing its catch *z* in the inside hole of the smaller disk *g* opposite the required number. Thus, if it is desired to 45 count fifteen hundred, place the catch *z* of the adjusting-arm *j* in the inside hole of the smaller disk *g* opposite "15," as this disk counts the hundreds. If it is desired to count five hundred and fifty, move the larger disk *f* round till "50" is opposite the latch *r*, thus 50 deducting the number less than one hundred. Then move the smaller disk *g* round till the cipher thereon is opposite "50" on the large

disk *f*. Then place the catch *z* of the adjusting-arm *j* in the inside hole of the smaller disk *g* opposite "6." Any other number may 55 be counted on the same principle.

The ratchet *c* is connected with the lever *b* through the circular slot *p* in the foundation *a*. The spring *d* holds the ratchet *c* in a notch of the large disk *f* until the lever *b* is 60 moved backward in the guide *t*, when the ratchet *c* is disengaged by the governing-pin *e*, which allows the ratchet *c* to drop into another notch of the disk *f*, when the lever *b* is released. Then by the force of the lever-spring *n*, the lever *b* and the disk *f* are moved 65 forward to the next figure-space, thus registering the count, and so on indefinitely.

When the counter is set for operation, as described, the figures in line opposite the latch *r* will show at any time the number counted. The smaller disk *g* revolves only once to the larger disk *f* one hundred times, for the catch *y* in the end of the latch *i* rests in a notch of the smaller disk *g* and does not allow it to 70 turn until the larger disk *f* has made a revolution. When the raised point *v* on the larger disk *f* in connection with the point *x* on the under side of the latch *i* raises the latch and allows the smaller disk *g* to be carried forward by the large disk *f* by pressure of the disk-spring *h*, which is convex, with its points bearing on the disk *f*, the distance of 75 one figure-space, thus counting the hundreds on the smaller disk *g*.

The bell-hammer *l* is held away from the bell *k* by the latch *r* until the adjusting-arm *j* is moved round by the regular working of the counter and strikes the latch *r* and disengages it, thus allowing the hammer *l* to strike the 80 bell *k* by the force of the hammer-spring *q*, giving notice that the number is counted. The counter may be used without the bell attachment, if desired.

When the counter is not needed, the lever 85 may be held out of adjustment by an eccentric *o* or other suitable device, allowing the machine to which it is attached to work independent of the counter.

The foundation on which the counter is 90 constructed may be made of wood or metal, and varied in form to suit the form of any machine to which it is applied.

For counting up to ten thousand, only two

disks are employed. For counting more than ten thousand, counters having three disks may be employed, all working on the same principle with reference to each other.

5 What I claim as my invention, and desire to secure by Letters Patent, is—

The combination, in a counting-machine, consisting, essentially, of two or three wheels or disks revolving on a common central pivot 10 notched and numbered 1 to 100, controlled by the spring *h*, the latch *i*, and the adjust-

ing-arm *j*, with the bell-hammer *l*, and the bell *k*, all operated by a ratchet-lever *b*, having the spring *n*, eccentric *o*, and ratchet *c*, with its spring *d* and governing-pin *e*, substantially as shown and for the purpose specified. 15

FRANK SWEET.
